UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

APPARATUS FOR CASTING STEREOTYPE PLATES.

No. 925,268.

Specification of Letters Patent. Patented June 15, 1909.

Application filed August 17, 1908. Serial No 448,893.

To all whom it may concern:

Be it known that I, HENRY F. BECHMAN, of Battle Creek, in the county of Calhoun and State of Michigan, have invented certain new and useful Improvements in Apparatus for Casting Stereotype-Plates; and I do hereby declare that the following is a full, clear, and exact description thereof, reference being had to the accompanying drawings, which form part of this specification.

This invention is an apparatus for casting stereotype plates, and is especially designed for casting single page tubular plates which are substantially complete cylinders and adapted to surround the surface of the plate cylinders to which they are attached in particular and the invention is an improvement upon the casting apparatus shown in my application filed December 5th, 1907, Serial No. 405,204 and its object is to enable a single tubular plate containing but one newspaper page of matter to be cast of a size and form to fit upon and surround small plate cylinders such as are used in connection with the novel rotary web printing machine shown in my Patents Nos. 867,230 and 867,231, dated October 1st, 1907.

The invention will be clearly understood from the following description in connection with the accompanying drawings, forming part thereof, and which shows the present perfected form of the apparatus, although I do not restrict myself to the precise details of construction shown as they are capable of modification by one skilled in the art within the scope of the present invention.

In the drawings: Figure 1, is side elevation of a complete apparatus, showing the parts in closed position, and also showing the cope and core in open positions in dotted lines. Fig. 2, is an enlarged top plan view of Fig. 1 also showing the cope in open position in dotted line. Fig. 3, is an enlarged sectional view on line 3—3, Fig. 1, showing a matrix secured in the machine, parts broken away. Fig. 4, is an enlarged sectional view showing the matrix holding devices and also showing the "side-stick" open in dotted line. Fig. 5, is a detail vertical sectional view showing the side-stick and core in position in the drag, the cope open. Fig. 6 is a detail perspective view of the side stick. Fig. 7 is a similar view of the core.

The machine embodies, a drag 1, which is preferably mounted in vertical position upon a supporting frame, composed of side pieces 7 and base plate 7^a. This drag has a semi-circular recess in its front face corresponding in contour to one half of the cylindrical plate to be cast in the machine.

The core 2, is cylindrical in cross section and corresponds in diameter to that of the press cylinder to which the plates are to be attached. The core has a circumferential flange 2^a which forms the bottom of the mold during the casting operations. The core is provided at its lower end with trunnions 2^b upon which are mounted rollers 2^c that rest upon the upper edges of the side pieces 7, and below these trunnions and in axial alignment with the core 2 and rigidly connected therewith is a weight or counter-balance 2^d which is calculated to practically counter-balance the weight of the core upon the trunnions and thus enable the core to be readily swung to either vertical or inclined position. The core is guided in its movements to and from the drag and prevented from running off the ways on side pieces 7 by means of arms 2^e which are rigidly fastened to the trunnions 2^b or lower part of core and may be cast therewith and are provided with pins 2^f which may be provided with rollers that engage curved guide slots 7^a in the side pieces 7, and not only limit the movement of the core, but cause it to swing to an inclined position when it is pulled away from the drag and to assume a vertical position when it is moved toward the drag. The upper end of the core is preferably beveled as at 2^g to form a gate and facilitate pouring of the metal into the mold; and it may be provided with a handle 2^h to facilitate raising or lowering of the core.

Hinged to one side of the drag 1 is a cope 3, which has a semi-circular recess in its inner face corresponding in contour to one-half the plate to be cast and slightly greater in diameter than the core and adapted when the core is in position in the drag to be closed against the drag and therewith completely surround the core, as indicated in Fig. 2, the space between the cope and drag and the interposed core forming an annular casting chamber into which metal can be poured through the gate 2^g at the top of the core. The cope may be fastened to the drag,

ner that it will naturally tend to force the matrix outward against the walls of the drag and cope and insure a clean and perfect casting.

5 It is obvious that such machines can be made to produce cylindrical tubular plates of any desired diameter and length and also if desired they can be adapted to cast a plurality of parti-cylindric plates by applying 10 suitable margin spaces to the core.

The novel means for fastening the matrix in the core facilitates casting of the plate as the operator only has to give attention to fastening one edge of the matrix which can be readily done with great accuracy and, 15 practically, the fastening of the other edge of the matrix is accomplished automatically by closing of the cope.

Having described my invention what I 20 claim as new and desire to secure by Letters Patent is:

1. In a stereotype casting machine the combination of a drag, a cope, a movable core, means for fastening one edge of a 25 matrix to the drag, and means for securing the other edge of the matrix between the core and the cope.

2. In a stereotype casting machine the combination of a drag a tiltable core, a swinging cope a yoke for binding the cope to the 30 drag and means for fastening the yoke.

3. In combination a drag having a casting recess, a core, movable to and from the drag, a cope movable to and from the drag and 35 adapted to inclose the core in the drag and a yoke hinged to the drag and adapted to press the cope thereagainst, and means for fastening the yoke.

4. In combination a drag having a casting 40 recess, a tiltable core movable to and from the drag, and a hinged cope having a casting recess and movable to and from the drag, and adapted to inclose the core in the drag with a yoke hinged to the drag and 45 adapted to press the cope thereagainst, and means for fastening the yoke.

5. The combination of a drag, a cope 50 hinged thereto, and having an exterior boss, a semi-circular yoke hinged to the drag and adapted to close upon the cope and engage the boss thereof, and fastening devices adapted to engage and lock the yoke.

6. The combination of a drag, a side stick 55 hinged thereto adapted to secure one edge of a matrix, a cope hinged to the drag, and means co-acting with the cope to secure the other edge of the matrix.

7. In combination a drag, a cope and a 60 core, means adapted to secure one edge of a matrix to the drag and means connected to the core to secure the other edge of the matrix.

8. In combination a drag, a cope and a 65 core, means connected with the drag to secure one edge of a matrix and means con-

nected with the core and adapted in connection with the cope to secure the other edge of the matrix.

9. In combination a drag, a cope and a core, means to secure one edge of a matrix to the drag, and a bar attached to the core to secure the other edge of the matrix. 70

10. In combination a drag, a cope and a core, a bar connected with said core and a side stick connected to the drag and adapted 75 to secure the edges of a matrix.

11. In combination a drag, a cope hinged thereto, a movable core, a bar on said core, and a side stick on the drag, adapted to co-act with said bar and form a marginal 80 space between the edges of the plate.

12. In combination a drag, a cope hinged thereto, a movable core, a bar on said core and a side stick hinged to the drag and adapted to co-act with the said bar and form 85 marginal space between the edges of the plate and to also secure the edges of a matrix.

13. In a stereotype casting apparatus, the combination of a drag, a core, movable to 90 and from the drag and a movable cope adapted to inclose the core in the drag with a bar at the side of the core and a matrix fastening device on the drag adjacent to the said bar, when the mold is closed. 95

14. In a stereotype casting apparatus, the combination of a drag, a core, movable to 100 and from the drag and a movable cope adapted to inclose the core in the drag, with a bar secured to the core and a matrix fastening device attached to the drag at a point adjacent to the said bar when the mold is closed.

15. In a stereotype casting apparatus, the combination of a drag, a tiltable core, movable to 105 and from the drag and a hinged cope adapted to inclose the core in the drag, with a bar secured to the core, adjacent the meeting line of the drag and cope, and a matrix fastening device attached to the drag at a 110 point adjacent to the said bar when the mold is closed.

16. In a stereotype casting apparatus, the combination of a drag, a core, movable to 115 and from the drag, and a cope adapted to inclose the core in the drag with a marginal bar adjacent the meeting line of the drag and cope, a side stick hinged to the edge of the drag at the side adjacent the said bar when the mold is closed and adapted to secure one edge of a matrix, said cope and bar 120 securing the other edge of the matrix when the mold is closed.

17. In a stereotype casting apparatus, the combination of a drag, a tiltable core, movable to 125 and from the drag and a hinged cope adapted to inclose the core in the drag and a bar secured to the core adjacent the meeting line of the drag and cope, with a side stick hinged to the edge of the drag at the 130

side adjacent the said bar when the mold is closed, and adapted to secure one edge of a matrix, said cope and bar securing the other edge of the matrix when the mold is closed and means for locking the parts in closed position.

18. In combination a drag, a core and a cope said core having a marginal bar on one side and having a gate on its upper end at 10 the side opposite the bar.

19. In combination a drag, a swinging core and a hinged cope said core having a bar on one side adapted to come adjacent the meeting edge of the core and cope when 15 the flask is closed, and having a gate on its upper end at the side opposite the bar.

20. In combination a drag, a core and a cope, said core having a bar on its side adapted to come adjacent the meeting edge 20 of the core and cope when the flask is closed and having a gate on its upper end, a matrix retaining device attached to the drag adja-

cent the said bar when the cope is closed and adapted to secure one edge of the matrix, the other edge of the matrix being retained 25 between the bar and cope.

21. In combination a drag, a swinging core and a hinged cope, said core having a bar on its side adapted to come adjacent the meeting edge of the core and cope when the flask is closed, and also having a gate on its upper end, opposite the bar, with a side stick hinged to the edge of the drag adjacent the side bar when the cope is closed, and adapted to secure one edge of a matrix, the 35 other edge of the matrix being retained between the bar and cope.

In testimony that I claim the foregoing as my own, I affix my signature in presence of two witnesses.

HENRY F. BECHMAN.
